(57) **CLAIM**

The ornamental design for a fastener-driver handle, as shown and described.

DESCRIPTION

FIG. 1 is a front perspective view of a fastener-driver handle showing the new design;

FIG. 2 is a bottom view of the fastener-driver handle;

FIG. 3 is a top view of the fastener-driver handle;

FIG. 4 is a left side view of the fastener-driver handle;

FIG. 5 is a right side view of the fastener-driver handle;

FIG. 6 is a front view of the fastener-driver handle;

FIG. 7 is a rear view of the fastener-driver handle; and,

FIG. 8 is a rear perspective view of the fastener-driver handle.

The broken lines in the drawings illustrate portions of the fastener-driver handle that form no part of the claimed design.
